CLAIM

The ornamental design for a meter garnish for automobile, as shown and described.

DESCRIPTION

FIG. 1 is a front left perspective view of the meter garnish for automobile showing my new design;

FIG. 2 is right front perspective view thereof;

FIG. 3 is a front elevation view thereof.

FIG. 4 is a top plan view thereof.

FIG. 5 is a left side elevation view thereof; and,

FIG. 6 is a right side elevation view thereof.

The portion of the article shown in broken lines is for illustrative purpose only and forms no part of the claimed design.
